UNITED STATES PATENT OFFICE.

FRANS PERSON, OF NORTH EASTON, MASSACHUSETTS.

UMBRELLA-STICK.

1,054,026.

Specification of Letters Patent.

Patented Feb. 25, 1913.

Application filed June 21, 1911. Serial No. 634,548.

To all whom it may concern:

Be it known that I, FRANS PERSON, a citizen of the United States, residing at North Easton, in the county of Bristol and State 5 of Massachusetts, have invented certain new and useful Improvements in Umbrella-Sticks, of which the following is a specification.

This invention relates to improvements in 10 umbrella sticks and its object is to produce a device of this class provided with a detachable handle adapted to be secured to either end of the stick.

With the foregoing and other objects in 15 view the invention consists in the combination and arrangement of parts to be herein-after fully described in the following specification, pointed out in the claims and illustrated in the accompanying drawing which 20 forms a part of said specification and in which—

Figure 1 is a view of an umbrella embodying my improved stick with the handle secured to one end of the stick. Fig. 2 is a 25 similar view with the stick reversed and the handle secured to the opposite end. Fig. 3 is a view of the naked stick with the handle partly in section. Fig. 4 is a view of the handle, partly in section, showing the 30 spring therein which assists in retaining the hinged handle sections in an adjusted position. Fig. 5 is another view of the handle in an altered position.

Like reference characters indicate corre- 35 sponding parts throughout the several views.

1 is an ordinary umbrella provided with my improved stick 2. Near either end of the stick I provide a plurality of annular recesses 3 while in other respects the stick 40 is much like the ordinary umbrella stick. My umbrella handle is made in two sections pivotally connected or hinged together as at 4, the lower section 5 being formed with a cylindrical bore throughout the greater part 45 of its length for the reception of either end of the umbrella stick. A plate 6 is secured upon the part 5 of the handle by a suitable screw 7 which pierces the handle and engages the body of the stick and the other 50 end of the plate 6 is provided with a pin 8 that also pierces the part 5 of the handle and rides in one of the annular recesses 3 of the stick. This arrangement affords a means for retaining the stick within the handle in variable positions as it is evident the pin 8 may 55 be manually withdrawn from the recess it is

temporarily riding in and the stick moved up or down as the case may be until the said pin engages another recessed portion.

Near the top of the part 5 of the handle 60 a cylindrical jacket 9 provided with alternately disposed U-shaped slots 10 is slidably arranged and a pair of oppositely disposed screws secured in the handle ride in the said slots for a purpose which will hereinafter 65 become evident. The upper section 12 of the handle which is secured, as previously set forth, to the lower section 5 by the pivot or hinge 4 is provided in an internally recessed portion as at B with a pin 13 to which one 70 end of a spring (also located in this internally recessed portion of the upper handle section) 14 is secured; the body of the spring being wound about the pivot 4 and its opposite extremity secured in the lower handle 75 section 5.

When the upper section 12 of the handle is bent at right angles to the lower portion the jacket 9 will reside entirely below the upper handle section and the tension of the 80 spring 14 will serve to keep the two portions in this position; to straighten the handle the section 12 is manually rotated upon the pivot or hinge 4 until it is in a straight line with the other handle portion and the 85 jacket 9 is then rotated until the screws 11 lie in the base of the U-shaped loops 10 when the said jacket is raised vertically until the 90 said screws reach the lower termination of the loop base and the jacket is then rotated 90 in a manner to place the screws in the lower extremity of the loop when the screws 11 will occupy the position illustrated in Fig. 4 and the pivot 4 and a portion of either 95 handle section will be encompassed by the jacket and the handle members locked in alinement with each other.

What I claim is:—

1. The combination, with the stick having a plurality of annular recesses adjacent either end, of a hinged sectional handle whose lower section is provided with a bore, a plate secured to the outer handle section, a pin extending through said plate and handle section for engagement with the recessed portion of the stick, a slotted jacket slidably arranged upon the lower handle section, screws secured in said handle section adapted to ride in the slotted portion of the jacket and a spring arranged upon the handle hinge and engaging the two handle sections. 105
2. The combination, with the stick hav-

ing a plurality of annular recesses adjacent either end, of a hinged sectional handle whose lower section is provided with a bore, means arranged on the lower handle section 5 for retaining the stick therein at variable positions, a slotted jacket slidably arranged upon the lower handle section, screws secured in said handle section adapted to ride in the slotted portion of the jacket and a

spring arranged upon the handle hinge and 10 engaging the two handle sections.

In testimony that I claim the foregoing as my own I have hereto affixed my signature in the presence of two subscribing witnesses

FRANS PERSON.
